UNITED STATES PATENT OFFICE.

EDWIN C. HOWE, OF BRIDGEPORT, CONNECTICUT.

DESIGN FOR A BRACKET FOR INCANDESCENT LIGHTS.

SPECIFICATION forming part of Design No. 26,492, dated January 5, 1897.

Application filed August 14, 1896. Serial No. 602,817. Term of patent 7 years.

To all whom it may concern

Be it known that I, EDWIN C. HOWE, a citizen of the United States, residing at Bridgeport, in the county of Fairfield and State of

5 Connecticut, have invented and produced a new and original Design for Brackets for Incandescent Lights; and I do hereby declare the following to be a full, clear, and exact description of the invention, such as will enable

10 others skilled in the art to which it appertains to make and use the same.

The accompanying drawing illustrates in perspective my newly-designed bracket.

15 The leading features of my design consist in the angular bend at or about the middle portion of the bracket, the loop or eye at one extremity of the bracket, and the cylindrical plug extending from the other extremity of the bracket.

20 The bracket is made from sheet metal with the exception of the plug, which is secured to the bracket in any suitable manner and is threaded so as to be readily attached within the socket of an incandescent light. The

25 loop or eye portion is formed by curving and

recurring the sheet-metal stock, and when viewed in side elevation such loop or eye as well as the threaded plug appear disposed in a horizontal plane.

1 is the sheet-metal bracket; 2, the loop or 30 eye at one end thereof; 3, the angular bend at or about the middle portion, and 4 the exteriorly-threaded plug, secured to the outer extremity of such bracket.

5 is a clamping-screw which passes through 35 the body and extremity of the stock which forms the loop or eye for the purpose of contracting or expanding such eye, as may be desired.

40 I claim—
The design for a bracket for incandescent lights, substantially as herein shown and described.

In testimony whereof I affix my signature in presence of two witnesses.

EDWIN C. HOWE.
